ABSTRACT OF THE DISCLOSURE

A compact vane-type pump is described which is particularly useful for dental hygiene purposes, but which has general utility. A vane is reciprocally mounted in an inner chamber in the pump, and the vane has a port extending through it with a flutter valve positioned in the port. The vane is reciprocally moved from one angular position to the other in the inner chamber during the operation of the pump, so as to draw fluid into the chamber and to force fluid out of the chamber, as will be described.

BACKGROUND OF THE INVENTION

In recent years oral irrigators have become a prevalent means for cleansing the mouth and teeth. These instruments operate to direct a high pressure fluid jet into the mouth and into the spaces between the teeth and gums. The improved vane pump of the present invention, as mentioned above, is particularly suited for oral hygiene purposes, since it may be constructed to be light and compact, and yet it is capable of delivering a highly pressurized jet of fluid through its outlet. However, as also mentioned, the pump of the invention has general utility.

The vane pump of the present invention, as will be described, may be constructed of appropriate non-corrosive material, such as nylon, and it may be driven, for example, by a shaded pole electric motor. When so driven, the pump is capable of producing a fine high velocity jet of fluid which pulsates, for example, at a rate of the order of 1300 pulsations per minute. The resulting fluid jet, as mentioned above, may then be directed against the gums of the user, or against other areas to be treated. The use of the relatively low frequency pulsations in the jet produced by the pump of the invention has been found to provide an effective massaging and stimulating action; so as to clean and manipulate the gum tissue, when the instrument is used for oral hygiene purposes.

SUMMARY OF THE INVENTION

The vane pump of the present invention is one in which a vane is pivotally mounted within a chamber on a drive shaft, and is driven by the drive shaft in a manner so that the vane is reciprocated angularly back and forth in the chamber. The vane divides the chamber into an inlet compartment and an outlet compartment. An inlet line extends into the inlet compartment, and an outlet line extends out from the outlet compartment. The vane has a port extending through it, and a flutter valve is positioned on the vane across the last named port. As the vane moves angularly in a first direction, it draws fluid into the inlet compartment of the chamber while, at the same time, driving fluid out of the outlet compartment. On the other hand, when the vane moves angularly in the opposite direction, the fluid in the inlet compartment passes through the port in the vane and into the outlet compartment.

2**BRIEF DESCRIPTION OF THE DRAWING**

FIGURE 1 is a front elevational view of a vane pump which may be constructed in accordance with the concepts of the present invention, and of a suitable electric motor for driving the pump;

FIGURE 2 is a side elevational view of the assembly of FIGURE 1;

FIGURE 3 is an exploded view showing in perspective the various components which make up the pump of FIGURES 1 and 2; and

FIGURE 4 is a front view of the pump, with the cover removed, and showing the action of the pivotally mounted vane within the pump.

15 DETAILED DESCRIPTION OF THE ILLUSTRATED EMBODIMENT

The pump of the present invention may be driven by an electric motor 10. The motor 10, for example, may be of the shaded pole type, as described above, so that it may be easily started and stopped, conveniently to control the action of the pump. The motor 10 has a drive shaft 12, and a pinion 14 is keyed to the end of the drive shaft. The motor is mounted on a mounting plate 18, by means of screws, such as the screws 11. The pinion 14 drives a second pinion 16 which is rotatably mounted on the mounting plate 18. An eccentric pin 20 on the pinion 16 extends into a slot in a lever arm 22, the slot being identified as 24.

30 A pump housing 28 is also mounted on the mounting plate 18. A rotor shaft 30 for the pump is rotatably supported in a bearing bushing 34 on the mounting plate. The rotor shaft 30 extends through an aperture in a cover member 31 which is supported on blocks 33 and 35 by means, for example, of screws 37 and 39 (FIGURE 1). The housing 28 is supported on the cover 31 by means of screws 41 (FIGURES 1 and 2), and O-rings 43 and 45 effectively seal the cover 31 and the housing 28, as well as the drive shaft 30 and the cover. 35 The lever arm 22 is coupled to the rotor shaft 30, by virtue of a rectangular sleeve 32 which is keyed to the rotor shaft and which extends through a corresponding rectangular aperture in the arm 22. A screw 47 is 40 threaded through the arm 22 so as to hold the arm tightly on the sleeve 32.

45 It will be appreciated that as the motor 10 rotates the pinion 16, the pin 20 causes the arm 22 to oscillate angularly back and forth, producing a similar angular oscillation to the rotor shaft 30 of the pump.

50 The pump casing 28 may be formed of an appropriate plastic material, such as nylon, or other suitable material, which is preferably noncorrosive. The casing 28 defines an inner chamber 49, and a vane 36, which is 55 mounted on the rotor shaft 30, is supported in the chamber. The vane 36 effectively divides the chamber 49 into two compartments. The compartment on one side of the vane may be termed the inlet compartment and a suitable inlet line 40 extends into that compartment. The vane 60 also divides the chamber 35 into an outlet compartment, and a suitable outlet line 42 extends from the outlet compartment.

65 The vane 36 is shaped to have a resilient peripheral portion 36a which engages the inner peripheral wall of the chamber 49 effectively to seal the inlet compartment from the outlet compartment. The vane 36 has a port 36b extending through it, and a check valve 44 of the flapper or flutter type is pivotally mounted on the vane adjacent the port 36b. The check valve 44 moves to close the port 36b when the vane moves in a clockwise direction, for example, to the left in FIGURE 4; and the check valve moves away from the port 36b effectively

to open the port when the vane moves in a counterclockwise direction to the right in FIGURE 4.

The operation of the pump is such that when the motor is energized, the vane 36 is caused to oscillate angularly within the chamber 49. Each time the vane moves in a counterclockwise direction in FIGURE 4, for example, the fluid in the inlet compartment passes through the port 36b into the outlet compartment. Then, when the vane moves in a clockwise direction, the check valve 44 closes, and the fluid in the outlet compartment is forced out through the outlet line 42 while, at the same time, additional fluid is drawn into the inlet compartment through the inlet line 40, so that the cycle may be repeated.

The invention provides, therefore, a simple and efficient vane-type pump which can be housed in a relatively small casing, and which is simple and easy to operate. Moreover, the pump may be constructed relatively inexpensively, and sold at a relatively low price.

While a particular embodiment of the invention has been described, modifications may be made. It is intended in the claims to cover the modifications which come within the scope of the invention.

What is claimed is:

1. A vane pump assembly including:
a mounting plate;
an electric motor mounted on one side of said mounting plate and having a drive shaft extending through said mounting plate;
a pump housing mounted on the opposite side of said mounting plate and defining an inner chamber having an inlet and an outlet;
a rotor shaft mounted on said mounting plate and extending through said inner chamber defined by said pump housing;
a lever arm coupled to said rotor shaft and extending radially with respect thereto;
eccentric means coupling said lever arm to said drive shaft to cause said lever arm to operate angularly back and forth upon rotation of said drive shaft thereby producing angular oscillations of said rotor shaft; and

40

a vane mounted on said rotor shaft and disposed in said inner chamber for reciprocal angular movement in said inner chamber, said vane having a port therein and check valve means mounted on said vane across said port, said vane being angularly movable by said rotor shaft in a first direction to draw fluid into said inner chamber through said inlet as said vane moves against fluid in said inner chamber to close said valve means and discharge said fluid out of said inner chamber through said outlet, and said valve being angularly movable by said rotor shaft in the opposite direction to open said valve means and cause fluid to pass through said port from one side of said vane to the other in said inner chamber.

2. The vane pump assembly defined in claim 1, in which said vane includes an integral resilient portion engaging a wall of said chamber and moving along said wall in sealing relationship therewith as said vane is moved angularly in said first direction.

3. The vane pump assembly defined in claim 1, in which said eccentric means includes a first pinion mounted on said drive shaft on the opposite side of said mounting plate from said motor; a second pinion rotatably mounted on said mounting plate and engaging said first pinion, and a pin mounted on said second pinion and extending axially therefrom, said lever arm having a slot therein for receiving said pin.
